DESIGN FOR WALLPAPER OR THE LIKE

William Burton, Chicago, Ill., and Dorothy W. Liebes, San Francisco, Calif.

Application April 30, 1947, Serial No. 138,721

Term of patent 3½ years

(Cl. D59—10)

To all whom it may concern:

Be it known that we, William Burton and Dorothy W. Liebes, citizens of the United States and residents of Chicago, in the county of Cook and State of Illinois, and of San Francisco, in the county of San Francisco and State of California, respectively, have invented a new, original, and ornamental Design for Wallpaper or the like, of which the following is a specification, reference being had to the accompanying drawing, forming a part thereof.

In the drawing the figure is a plan view of a wall paper showing our new design. The design unit is outlined by broken lines. Said unit repeats over the wall paper as indicated by the extensions beyond the unit boundaries.

We claim:

The ornamental design for wallpaper or the like, as shown and described.

WILLIAM BURTON.
DOROTHY W. LIEBES.
